TAKE-UP MECHANISM

Richard K. Hohmann, Jamaica, N. Y., assignor
to White Sewing Machine Corporation, Cleve-
land, Ohio, a corporation of Delaware

Application January 15, 1945, Serial No. 572,930

2 Claims. (Cl. 112—241)

1

The present invention relates to sewing machines, and particularly to domestic sewing machines of the type comprising side by side needle and presser bars, a take-up mechanism, and needle bar and take-up mechanism operating parts, all mounted in the hollow head portion of a sewing machine frame, and the general object of the present invention is to improve sewing machines of the type specified in respect to the form and disposition, or relative arrangement, of the above mentioned sewing machine elements.

My prior Patent 1,393,127 of October 11, 1921, discloses a practically desirable and commercially successful combination of needle bar, take-up mechanism and operating connection parts through which said bar and mechanism are connected to a common drive shaft transverse to the needle bar, the take-up mechanism of said combination including an oscillating arm carried by a rock shaft. The latter is parallel to the drive shaft and which is displaced in the same direction from the adjacent end of said shaft and from each of said bars, and intersects the plane including the axes of both bars.

A specific object of the present invention is to improve said combination so as to permit the length, weight and inertia of the rock shaft to be reduced, and so as to permit the use of the improved combination in sewing machines in which the relative arrangement of the two bars and the rock shaft prevents the latter from extending to said plane.

The various features of novelty which characterize my invention are pointed out with particularity in the claims annexed to and forming a part of this specification. For a better understanding of the invention, however, its advantages, and specific objects attained by its use, reference should be had to the accompanying drawings and descriptive matter in which I have illustrated and described a preferred embodiment of the invention.

Of the drawings:

Fig. 1 is a front end elevation of the head portion of a sewing machine frame with the cover plate removed;

Fig. 2 is a view taken similarly to Fig. 1 but showing parts in different positions; and

Fig. 3 is a section on the line 3—3 of Fig. 2.

In the construction shown in the drawings, A is the hollow head portion of a sewing machine frame, and A' is the removable cover plate normally closing the open front end of the chamber B in the head A. The head A is provided with separate upper and lower bearings for a needle

2

bar C and a presser bar D. As shown, the presser bar may be manually raised and lowered by a lever D' of conventional form. The bars C and D are adjacent but spaced away from one another and have their parallel axes transverse to the axis of the rotating drive shaft E which gives the needle bar its up and down movements, and which also gives oscillating movements to a take-up arm F. The latter is carried by a rock shaft G parallel to the drive shaft E and displaced therefrom to the rear, or left as seen in Figs. 1, 2 and 3. Advantageously and as shown, the rock shaft G is hollow and is mounted on a stationary shaft G' having its end remote from the cover plate A' secured to the head A.

The end of the driving shaft extending into the chamber B carries a crank disc H cut away for balancing and weight reducing purposes. At its side facing the cover plate A', the disc H carries a crank pin I, the free end of which is secured to and carries an arm J spaced away from the front end of the disc H at its end remote from the crank pin I. The arm J carries a crank pin K which is parallel to the shaft E and laterally displaced from the latter. The parts H, I, J and K, collectively form a crank shaft portion of the shaft E including crank shaft portions, formed by the pins I and K, which are parallel to the main shaft E and which have their respective axes laterally displaced in different directions, and for different distances from the axis of the shaft E.

The crank pin K gives up and down movements to the needle bar C through a link L pivotally connected at its upper end to said crank pin J and having its lower end pivotally connected to, the needle bar by a pivot M. The crank pin I gives oscillating movements to the rock shaft G through an arm O secured to the rock shaft G, and a block P journaled on the crank pin I, and formed with a passage transverse to and at one side of said pin through which the arm O extends and in which said arm is longitudinally movable.

Insofar as above described, the needle bar C, take-up arm F, and their operative connections to the common drive shaft E, do not differ from corresponding parts shown in my above mentioned prior patent. The improved construction disclosed herein differs from the construction disclosed in the prior patent, however, in two practically important respects, namely, in respect to the length of the rock shaft G, and in respect to the form of the take-up arm F and its disposition relative to the needle bar C and presser bar D.

In my prior patent, the rock shaft giving the

take-up arm its oscillating movements, has its end remote from the cover plate A' connected to and located relatively to the corresponding crank shaft portion of the driving shaft substantially as shown in the accompanying drawings. In the prior construction, however, the rock shaft is elongated so that it extends to the opposite side of the needle bar and presser bar from that at which the operating connection between the rock shaft and driving shaft is located. In said prior patent, the take-up arm is substantially straight and at the opposite side of both needle bar and the presser bar from the operating connection between the rock shaft and driving shaft.

In the improved construction, as is clearly shown in Fig. 3, the rock shaft is sufficiently short so that the shaft lies wholly to the side of the presser bar remote from the cover plate A', and the take-up arm F is offset so that its portion connected to and adjacent the rock shaft lies at the rear of the presser bar while its free end portion is in front of the needle bar, and an intermediate connection portion F' extending between the two bars. With the take-up arm F shaped as described, the shortening of the rock shaft G does not prevent the free end of the arm from moving the thread passage formed in it along the same path of movement which has been shown to be desirable in the extensive commercial use of the construction of my prior patent. The reduction in the length, weight and inertia of the rock shaft is practically desirable from the construction and operation standpoints, and reduces the tendency to and risk of objectionable vibration.

Moreover, as is clearly shown in Fig. 3, the shortening of the rock shaft permits the latter to be located so that if longer it would extend into engagement with the presser bar. The shortening of the shaft thus permits the type of take-up mechanism shown in said prior patent to be employed in sewing machines of a design now in commercial use, in which the needle bar and presser bar are spaced too widely apart to permit the rock shaft of the take-up mechanism to extend past the presser bar as it does in said prior patent, unless changes are made in the relative proportions of the take-up mechanism which would be objectionable from the construction standpoint, and because they would tend to produce objectionable oscillation.

While in accordance with the provisions of the

statutes, I have illustrated and described the best form of embodiment of my invention now known to me, it will be apparent to those skilled in the art that changes may be made in the form of the apparatus disclosed without departing from the spirit of my invention as set forth in the appended claims, and that in some cases certain features of my invention may be used to advantage without a corresponding use of other features.

Having now described my invention, what I claim as new and desire to secure by Letters Patent, is:

1. The combination with a sewing machine 15 needle bar and a rotating drive shaft extending transversely to a plane which is parallel to the axis of, and intersects said bar and comprising two crank portions at one side of and at different distances from said plane and a connection between one of said crank portions and said bar through which the rotating drive shaft reciprocates said bar, of a rock shaft parallel to and laterally displaced from said drive shaft and at said one side of said plane, a connection between 20 said rock shaft and the second of said crank portions through which said rotating shaft oscillates said rock shaft and a take up arm secured at one end to said rock shaft and having thread engaging means adjacent its other end and having its portion adjacent the rock shaft at said one side of said plane and having its end portion remote from said rock shaft at the opposite side of said plane and extending past said bar and having an intermediate portion extending 25 through said plane.

2. A combination as specified in claim 1, comprising a presser bar parallel to said needle bar and in position to be intersected by the portion of said plane nearest to said rock shaft and in 30 which the said intermediate portion of said take up arm extends between said bars.

RICHARD K. HOHMANN.
